UNITED STATES PATENT OFFICE.

IRA SHANNON DOWNING, OF CLEVELAND, OHIO, ASSIGNOR TO THE CURTAIN SUPPLY COMPANY, OF CHICAGO, ILLINOIS, A CORPORATION OF NEW JERSEY.

TICKET-HOLDER.

1,137,846.

Specification of Letters Patent.

Patented May 4, 1915.

Application filed September 21, 1912. Serial No. 721,706.

To all whom it may concern:

Be it known that I, IRA SHANNON DOWNING, a citizen of the United States, residing at Cleveland, in the county of Cuyahoga and State of Ohio, have invented certain new and useful Improvements in Ticket-Holders, of which the following is a specification.

My invention relates to ticket holders, and refers particularly to ticket holders used in connection with curtains for railway cars.

It is the object of my invention to provide a ticket holder which shall be efficient in operation, readily accessible to the passenger and ticket collector, while at the same time it shall be in such position that the ticket is not liable to be displaced when passengers enter or leave the car seats. In carrying out the invention, it is proposed to mount the ticket holder on the curtain, and in order that the curtain may not be unbalanced by the presence of the holder, and also in order that there may be a satisfactory support for the holder, it is mounted on the cover plate or escutcheon plate commonly provided at the middle of the bottom portion of the curtain and through which project the handles or finger pieces of the endwise movable rods that frictionally engage the sides of the window frame to hold the curtain at any desired elevation. These and other advantages of my invention will be more readily understood by reference to the accompanying drawings, which show a preferred embodiment of my improvements, and in which—

Figure 1 is a front elevation of a portion of the inside of a car, showing my improved ticket holder applied to a curtain; Fig. 2 is a transverse vertical section through a portion of the curtain showing my ticket holder applied to the cover plate used in connection with the locking mechanism of the curtain; and Fig. 3 is an enlarged front elevation of a portion of the curtain showing my ticket holder applied thereto.

The curtain 10, of the usual and well-known construction, is supplied with locking rods controlled by the handles 11, which project through suitable apertures in the

cover plate 12. The cover plate 12 has a vertical extension 13 parallel to the curtain 10. The spring holder 14 is applied at its ends to the cover plate 12, and is held in position by means of the screws or rivets 15. The spring 14, as clearly shown in Figs. 1 and 3, follows the outline of the extension 13.

As clearly shown in Figs. 1 and 2, a ticket 60 may be held in position between the extension 13 and the spring 14, and if desired the ticket may be held between the extension 13 and the curtain 10.

From the foregoing description, it will 65 be apparent that the present invention is in the nature of an article of manufacture designed exclusively for use in connection with the curtains of railway cars, one element of the holder being the ordinary escutcheon 70 plate, in which no change is made except that it is provided with an integral upstanding extension along its upper edge. The extension of the escutcheon plate in coöperation with the curtain constitutes a ticket 75 holder, and said escutcheon plate also provides a rigid and durable support or foundation for the spring clip which coöperates with the extension to grip a ticket between said members.

It will be apparent to those skilled in the art that considerable change could be made in the detailed construction of my ticket holder without departing from the spirit or scope of my invention.

What I claim is:

1. A new article of manufacture, an escutcheon plate for railway car curtains, said plate being bowed transversely and provided with an integral upstanding extension rising from the upper edge of the curved bowed portion throughout the length thereof, said extension constituting the back of a ticket holder, and an inverted substantially U-shaped spring clip having its upper portion lying in front of and in close proximity to the extension, the lower portions of the legs of the clip being shaped to conform to the convex face of the escutcheon plate and secured thereto.

2. As a new article of manufacture, an escutcheon plate provided with means for

attachment to an object, said plate being further provided with an upstanding extension rising from its upper edge throughout the length thereof, and an inverted substantially U-shaped spring web having its upper portion lying in front of and in close proximity to the extension, the lower portion of

the legs of the web being arranged to conform to and being secured to the face of the escutcheon plate.

IRA SHANNON DOWNING.
